RECORD STRIP CONTROL FOR MANI-FOLDING MACHINES

Carl Robert Mabon, Niagara Falls, N. Y., assignor to Gilman Fanfold Corporation, Limited, Niagara Falls, N. Y., a corporation of Ontario, Canada

Application April 24, 1931, Serial No. 532,501
Renewed June 30, 1934

21 Claims. (Cl. 197—133)

This invention relates to improvements in manifolding record machines, such as typewriting or billing machines, wherein a plurality of relatively superposed work webs or paper record

strips are employed, being supported in work position upon a writing bed or platen for the reception of inscriptions which may be made by the use of a typewriting machine, or by other means, transfer material such as carbon sheets being employed to transfer the records to the lower of the relatively superposed record strips in a familiar manner.

It is a general object of the invention to provide in machines of the class mentioned, an improved record strip positioning and smoothing mechanism of simple and practical construction and arrangement, whereby a number of superposed record strips of the continuous traveler type may be effectually maintained at all times in correctly aligned position upon the writing platen, and in smooth flat condition thereon without creases, wrinkles, bulges or depressions, or similar irregularities whereby clear, full and legible manifold inscription upon all of the record strips is assured.

Another and more particular object of the invention is to provide in machines of the class mentioned, an improved record strip positioning and aligning mechanism which is particularly effective and certain in seeking out and entering the strip aligning apertures in order that the strip aligning and positioning function may be attained with certainty and efficiency.

It is a further object of the invention to provide a strip controlling mechanism including an improved strip aperture engaging means which is especially effective in engaging the strip apertures as the strips are forwardly fed, and also effectively maintains its strip aperture engagement during the strip controlling operations.

Still another object of the invention is to provide for machines of the class mentioned, a strip controlling mechanism including an improved strip aperture engaging means which is especially effective in maintaining its controlling engagements with the apertures, being also constructed and arranged in an improved manner to assure free disengagement thereof from the apertures without undue binding against the aperture walls and without tearing or other injury to the latter.

A further object of the invention is to provide for machines of the class mentioned, a record strip controlling mechanism provided with one or a plurality of strip aperture engaging pins of improved construction and arrangement whereby

they are caused to enter strip apertures with greater certainty than in pre-existing devices, and when entered to engage and hold the strips more positively.

Other objects of the invention will be in part pointed out in the following detailed description of an illustrative but preferred embodiment of the invention and will be in part obvious in connection therewith.

The invention accordingly comprises the features of construction, combinations of elements, and arrangement of parts, which will be exemplified in the construction hereinafter set forth and the scope of the application of which will be indicated in the claims.

For a more complete understanding of the nature and objects of the invention, reference is had to the following detailed disclosure of the preferred embodiment and to the accompanying drawings, in which:

Fig. 1 is a side view in perspective of a writing machine of the flat platen type equipped with the invention;

Fig. 2 is an enlarged vertical longitudinal sectional elevation of the improved record strip controlling mechanism, the section being taken substantially on the line 2—2 of Fig. 3;

Fig. 3 is an enlarged fragmentary plan showing the arrangement of the improved controlling mechanism;

Fig. 4 is a fragmentary longitudinal vertical section similar to that of Fig. 2 but showing the parts in a different position;

Fig. 5 is a view similar to Fig. 4 but showing another position of the parts;

Fig. 6 is a fragmentary longitudinal vertical section showing the forward record strip holding means; and

Fig. 7 is a fragmentary partially diagrammatic view of the operating connections for the forward strip holding means.

Reference is made to the drawings for a detailed description of the embodiment of the invention there shown disclosing the improved controlling mechanism as applied to a writing machine of the flat platen type for which it is well adapted. The machine shown includes a supporting frame 10 including spaced pedestals 11 arranged to rest upon the floor for supporting the main operating parts in accessible operating position. Spaced supporting rails or frame members 12 connected by appropriate transverse frame members or tie rods 13 constitute the principal supporting frame work for the bed of the machine, being attached to the upright support-

- ing frame 10 in any suitable manner. Supported between the frame members 12 in any preferred manner is the platen 14 shown as being of the flat type and arranged for supporting the record strips S in smooth flat condition for the reception of the impressions of the type of the typewriting machine (not shown) which is mounted upon the rails 12 for movement over the platen in a well known manner.
- 10 Appropriate supporting means is provided for supporting the transfer or carbon sheets C in interleaved position with the record strips S over the platen 14. Any preferred supporting means may be provided for this purpose, a carbon sheet 15 roll 15 being shown as mounted at one side of one of the rails 12, the sheets C being wound thereon whereby they may be unrolled to extend transversely of the platen 14 to the opposite side of the latter where they may be secured in any appropriate manner.
- 10 The record strips S are of the continuous traveler type and as many strips as desired may be arranged in relatively superposed manifolding relation and led forwardly together from the 15 supply into writing position upon the platen. These record strips may be conveniently folded along successive transverse lines into a zigzag folded supply pack such as indicated at S' which is supported in any appropriate manner. Each 20 strip of the record strips is provided with strip controlling apertures S2 preferably arranged in two longitudinal series along the strips. Also each strip is preferably provided with a longitudinal series of blank forms or spaces for receiving the 25 written data and each strip may also be divided into a longitudinal series of record leaves or pad leaves S3 conveniently separated from each other by transverse lines S4 which may conveniently be weakened severance lines arranged or spaced coincidently with the fold lines of the supply pack S'.
- 10 The record strips S may be restrained or held at the forward end of the machine beyond the platen 14 by means of an appropriate strip securing device indicated generally at 18, an illustrative form of which is shown in Fig. 6. As 25 shown there is a transverse strip guiding plate 17 mounted in which are strip engaging pins 18 spaced to correspond with the lateral spacing of the strip apertures S2 so as to enter the latter when the strips are forwardly fed. These pins are preferably stationary as shown, the forward or strip engaging faces or sides being constructed or provided with an overhanging lip 19 so as to 30 provide retaining lugs adapted to overlie the strips at the forward edges of the apertures thus avoiding accidental disengagement of the strips after the pins have been placed in position in the apertures. The top face or surface of the pins 35 18 may, as shown, be rearwardly and downwardly inclined in a continuously inclined surface 20 from the lip 19 to the forward terminal of the pins which is preferably at or near the base of the pin adjacent to the guiding and supporting plate 17. When the strips are fed forwardly, they will be carried upwardly over this inclined surface 20, thus moving them to disengaged position with the pin; but when they are moved rearwardly, the lip portion will enter the apertures, thus guiding the pin into aperture engaging position, holding the strips securely against rearward movement and resisting strip disengagement.
- 10 A strip restraining bar or clamp 21 cooperates 40 in conjunction with the pins 18 to retain or hold

the strips against displacement at their forward ends. This clamping bar may be provided with a recess at its under side for the reception of the pins 18 and it may be controlled or operated manually by means of the mechanism diagrammatically shown in Fig. 7. This includes pivoted supporting levers 22 pivoted at 23, to one end each of which the bar 21 is attached. The operating link 24 controlled by the pedal 25 is connected to the opposite end of the levers 22, while a tensioned spring 26 is connected to the levers to hold the clamping bar 21 normally in strip restraining position. The release of the bar will thus be effected by manual operation of the pedal 25.

15 Spaced rearwardly of the bed of the machine from the strip securing device 18 and preferably to the rearward of the platen 14 is a second strip restraining and controlling mechanism indicated generally at 27. This controlling mechanism 20 may be in the form of an attachment applicable in operative position to completed billing or like machines.

15 This controlling mechanism 27 includes a suitable supporting frame 28 adapted to be attached 25 to the frame of the machine and arranged to support the operating parts of the mechanism. Spaced parallel guiding track rails or bars 29 are carried by the frame 28 extending longitudinally of the machine. A carriage 30 is supported for 30 longitudinal reciprocation upon the rails 29 through grooved rollers 31. The carriage 30 is thus restrained for longitudinal reciprocation adjacent to and substantially parallel to the path of the record strips. An adjustable tensioned spring 35 32 is connected to the carriage and anchored as at 33, being normally tensioned to urge the carriage in a rearward direction.

10 Strip engaging pins 34 are mounted upon the carriage 30 for longitudinal reciprocation therewith, there preferably being two such pins mounted upon a unitary supporting bar 35 and spaced apart laterally the same as the spacing of the strip apertures S2. The supporting bar 35 is provided with a rearwardly extending arm 36 45 pivotally mounted as at 37 upon the carriage 30 to the rearward of the pins 34. Thus, the pins may be swung upwardly and downwardly upon the mounting pivot 37 into and away from strip engaging position. The carriage plate 30 is preferably provided with elongated apertures 38 for the reception of the pins 34. The path of the record strips lies immediately above the carriage 30 as clearly shown in Fig. 4, so that the aligning pins 34, when protruding upwardly through the 50 apertures 38, will lie immediately in the strip path in position to contact with the strips and to enter the apertures S2 thereof when the latter are brought into alignment with the pins.

10 Each of the strip aperture engaging pins 34 is 55 provided at the rearwardly facing aperture engaging side thereof with a lip or extension 39 preferably as shown inclining upwardly and rearwardly from the body of the pin which is preferably cylindrical presenting a cylindrical aperture 60 engaging surface disposed beneath the protruding lip 39. This upwardly rearwardly inclining lip is preferably quite thin or chisel-edged at its strip engaging edge and is preferably rounded so as to 65 present a convex engaging edge, or is similarly shaped to adapt it to readily enter strip apertures when the latter are advanced into engagement with the lip.

10 The forwardly facing side of each pin 34 is 70 preferably formed to provide the rearwardly and 75

upwardly inclined surface 40. This surface preferably converges with that at the opposite side of the pin so as to present the chisel-edged strip engaging lip 39. The surface 40 is preferably sloped off quite considerably toward the base of the pin as shown so as to adapt it to swing out of aperture-engaging position without injury to the aperture walls. For this purpose surface 40 may be curved substantially concentric with the pivot 5 mounting 37. This surface is also preferably rounded transversely of the pin axis so as to present a surface which is convex transversely of the strip path this formation also enabling the pin to engage or disengage smoothly with the strip 10 apertures, and without injury to the walls of the latter. The pins are preferably provided with threaded supporting shanks 41 whereby they are firmly attached in correctly aligned position to supporting bar 35.

20 A stressed spring 42 normally urges the pin supporting bar 35 into normal position shown in Figs. 2 and 4, and the pins may be retracted by a manually operated mechanism. For this purpose, an operating lug 43 is mounted for longitudinal reciprocation in a supporting bracket 44 attached to the bar 35, said lug being yieldingly urged into extended or operative position by means of a compression spring 45. The upper side of the lug 43 is flat, while its underside has an inclined surface 46 adapted to engage with the operating plunger 47 mounted for vertical movement in a supporting bracket 48 carried by the framework 28. A spring 49 is connected to the operating plunger 47 normally urging the latter into its upper operative position as shown in Figs. 2 and 4. This operating plunger is connected by an adjustable link with the operating pedal 25. The operating plunger is thus positioned for engagement with the upper flat face of the retractable lug 43 when the carriage 30 is moved forwardly with the record strips against the tension of spring 32 to the position shown in Fig. 4. Forward movement of the carriage may be limited by the brackets 57 which thus function as stop lugs and may be provided with cushion bumpers. When thus positioned, depression of the plunger 47 by operation of the pedal 25 will swing the pins 34 downwardly about the pivotal point 37 as an axis.

50 Guiding means are preferably provided to guide the record strips yieldingly into engagement with the aligning pins, the strip guiding tensioned spiral springs 53 being very convenient and desirable for this purpose. These guiding springs 53 are preferably mounted in operative position by suspending them in tensioned condition upon a movable supporting frame 54 pivotally mounted for swinging movement at 55 near one side of the carriage.

60 Although the strip guiding and supporting frame 54 does not form a part of the present invention except in combination, it may be noted that the side bars extend transversely of the record strip path immediately above the latter, whereby it may be swung upwardly upon its pivotal support 55 away from operative position. Spring retaining clamps 56 together with supporting brackets 57 are preferably provided for supporting the swinging guiding frame 54 in its operating position. The flexible and pliable guiding members or springs 53 are thus positioned with their longitudinal dimensions extending substantially longitudinally of the strip path and they are positioned adjacent to the strip controlling pins 34 so as to yieldingly position the record strips

in their feeding movements in position for proper cooperation with said pins.

The objects and nature of the invention having been set forth and an illustrative embodiment described in detail, the operation of the improved device, embodied in large degree in the above description, will now be clear and may be briefly summarized as follows:

Any desired number of record strips may be assembled and fed forwardly into writing position 10 upon the platen 14 either by hand, or if desired, by an appropriate feeding mechanism. Prior to this feeding movement, the record strip controlling device including the pins 34 will occupy the position shown in Fig. 2, the controlling carriage 15 5 then being in its rearward retracted position in which it is yieldingly held by the spring 32.

As the record strips are thus fed forwardly, they are yieldingly urged by the pliable guide springs 53 into cooperative relation with the controlling pins 34. Thus, the pins occupy an advantageous position for seeking out and entering the controlling apertures S2.

If the strips are slightly out of alignment with each other either transversely or longitudinally 25 thereof, the novel pin structure described including the lip portion 39 is especially well adapted to seek and enter the apertures even though said apertures may be obstructed by the transverse or longitudinal disalignment of the strips. Even 30 when the apertures are nearly or fully closed by such disalignment, these pins are very efficient in finding their way into all of the apertures, thus aiding greatly in bringing the strips into correctly aligned superposed relation with each 35 other.

Continued advancement of the strips after the pins have entered the apertures will cause the controlling carriage 30 to move forwardly against the tension of spring 32 until the forward strip 40 apertures are brought a short distance in advance of the forward pins 18 before being checked by the brackets 57. The strips are then allowed to retract rearwardly slightly by virtue of the tensioned spring 32, causing the hooked ends of the 45 pins to be entered in the strip apertures and bringing said apertures against the forward lipped side of the forward pins 18. The record strips are aligned, tensioned, and smoothed in correct writing position over the platen 14, whereupon the inscription may be made.

When the record strips are fed forwardly as just described, it will be understood that the pedal 25 is depressed, thus raising the front strip retaining bar 16 to release the forward ends 55 of the strips, and at the same time depressing the operating plunger 47. Therefore, when the carriage 30 moves forwardly with the advancing strips, the operating lug 43 for the pins 34 will be positioned to directly overlie the operating plunger 47. Upon release of the pedal, the plunger 47 is moved upwardly by spring 49 engaging the inclined surface 46 to cause retraction of the lug 43 until the plunger 47 occupies the operative overlying position as shown in Fig. 65 4. The parts occupy this position during the writing operation.

After completion of the writing, the next operative cycle may be initiated. That is, the inscribed parts of the record strips are fed forwardly as above described, whereupon they may be torn off across the forward edge of the bar 16, or they may be severed in any other preferred manner. As the pedal 25 is depressed preceding this strip feeding action, descent of the plunger 75

47 carries the pin supporting bar 35 downwardly about the pivotal support 37 thereof. This pivotal movement causes the controlling pins 34 to descend with a pivotal or rotary motion about the point 37 so as to carry the aperture engaging side of the pins slightly forwardly longitudinally whereby the pins are caused to disengage the apertures with an aperture freeing action. By virtue of this action the lipped strip engaging portions 39 of the pins are carried forwardly to a sufficient extent to free the walls of the apertures, thus avoiding obstruction to pin withdrawal, or tearing or otherwise marring the aperture walls. Also, during this aperture disengaging movement of the controlling pins, the convexed or curved surfaces 48 of the pins are effectual in avoiding any obstruction or injurious engagement of this side of the pins with the opposite or forward walls of the strip apertures. Therefore, by virtue of this arrangement, the pins may readily be withdrawn from aperture engagement without any obstruction whatsoever and without any tearing or marring of the strips. At the same time the lipped construction 39 of the controlling pins not only greatly aids entry of the pins into aligning and controlling position in the apertures, as above described, but it also aids very materially in retaining the strips in controlling engagement with the pins, largely because of the strip overlying lips or extensions 39. When the pins are fully withdrawn from the aperture as shown in Fig. 5, the carriage is freed from the strips S and is returned by the spring 32 to its initial position, as shown in Fig. 2. In order further to facilitate the withdrawal of the controlling pins 34 from engagement with the strip apertures, the lugs 52 are placed upon the plunger 47 in position to engage with the bifurcated bracket 51 when said plunger is being elevated upon pedal release and the controlling carriage 38 is in its forwardly moved position as shown in Fig. 4. As the plunger 47 is thus raised by action of the spring 49, the pins or lugs 52, as they engage with the convexly curved surfaces of the bracket 51, will impart a slight forward movement to the carriage 38, thus moving the pins 34 slightly away from engagement with the adjacent rear walls of the strip apertures S2. However, just prior to this forward movement of the controlling carriage, the strip gripping clamps 14' positioned to the rearward of the writing area of the platen 14 will have been set so as to clamp the strips in smoothed writing position on the platen while said strips are still under the smoothing and tensioning influence of the controlling carriage. It will be understood that the strip clamping device 14' may be similar to those commonly used in machines of this type and therefore are herein disclosed diagrammatically merely. As shown thus diagrammatically in Fig. 7, the clamping device 14' is released from strip clamping position when the pedal is depressed as for example by depressing the rearward edge or end of the platen 14 slightly by means of the operating connection 24' between the operating link 24 and the platen. The strip supporting surface of the platen is thus moved slightly away from clamping members 14' which may be stationary, thus releasing the grip at the opposite edges of the strips.

Thus, when the controlling carriage 38 is forwardly moved as just described by actuation of the plunger 47, the strips have already become clamped at their forward end by the clamp 21 and at the rear end of the platen by the clamp-

ing devices 14'. The forward movement of the carriage therefore moves the pins 34 away from the strip aperture walls as described. Being thus freed from engagement with the aperture walls the pins 34 may move freely to disengaging position as the plunger 47 descends thus further insuring that no tearing or other damage to the strip apertures will be caused when the pins are withdrawn. Also, it will be observed that the rearward movement of the carriage after withdrawal of the pins 34 from strip engaging position cannot be initiated until the lugs 52 have passed downwardly beyond the end of the bracket 51. This prevents any premature movement of the carriage which might result in damage to the strips or to the walls of the strip apertures.

Since certain changes may be made in the above construction and different embodiments of the invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:—

1. In a record machine, in combination, a writing platen over which a record strip having apertures may be fed and supported for the reception of an inscription, strip controlling means for controlling the strip on said platen and including a pin having a rearwardly facing lipped strip aperture engaging portion, a mounting device supporting said pin for forward and rearward movement in the strip path and means mounting said pin for movement away from strip aperture engaging position with a longitudinal strip freeing movement whereby said lipped portion is freed from engagement with the edge of the strip aperture.

2. In a record machine, in combination, a writing platen over which a record strip having apertures may be fed and supported for the reception of an inscription, strip controlling means for controlling the strip on said platen and including a pin having a rearwardly facing lipped strip aperture engaging portion and a pivotal mounting for said pin the pivot point of which is displaced longitudinally of the strip path to the rearward of the lipped side of said pin whereby said pin may swing on its pivot away from the aperture wall to free the lipped portion of the pin from said wall.

3. In a record machine, in combination, a writing platen over which a record strip having apertures may be fed and supported for the reception of an inscription, strip controlling means for controlling the strip on said platen and including a pin having a rearwardly facing lipped strip aperture engaging portion, a pivotal mounting for said pin the pivot point of which is displaced longitudinally of the strip path to the rearward of the lipped side of said pin whereby said pin may swing on its pivot away from the aperture wall to free the lipped portion of the pin from said wall and a mounting device supporting said pin for forward and rearward movement in the strip path.

4. In a record machine, in combination, a writing platen over which a record strip having apertures may be fed and supported for the reception of an inscription, strip controlling means for controlling the strip on said platen and in-

cluding a pin having a rearwardly facing lipped strip aperture engaging portion and mounting means mounting said pin for strip disengaging movement and for simultaneously forward longitudinal movement whereby said lipped portion is freed from engagement with the strip aperture wall.

5. In a record machine, in combination, a writing platen over which a record strip having apertures may be fed and supported for the reception of an inscription, strip controlling means for controlling the strip on said platen and including a pin having a rearwardly facing lipped strip aperture engaging portion, mounting means 10 mounting said pin for strip disengaging movement and for simultaneous forward longitudinal movement whereby said lipped portion is freed from engagement with the strip aperture wall and a rearwardly urged mounting carriage supporting 15 said pin for forward and rearward movement substantially in the strip path.

6. In a record machine, in combination, a writing platen over which a record strip having apertures may be fed and supported for the reception of an inscription, strip controlling means 20 including a pin positioned rearwardly of the platen and having a rearwardly facing lipped strip aperture engaging portion, a longitudinally spaced aperture engaging pin positioned forwardly of the platen and having a forwardly facing aperture engaging lipped portion and a mounting device mounting one of said longitudinally spaced pins for strip disengaging movements and for simultaneous longitudinal movement 25 whereby said lipped portion is freed from engagement with the strip aperture wall.

7. In a record machine, in combination, a writing platen over which a record strip having apertures may be fed and supported for the reception of an inscription, strip controlling means 30 including a pin positioned rearwardly of the platen and having a rearwardly facing lipped strip aperture engaging portion, a longitudinally spaced aperture engaging pin positioned forwardly of the platen and having a forwardly facing aperture engaging lipped portion, a mounting device mounting said rearward pin for strip disengaging movement and for simultaneous forward longitudinal movement whereby the lipped portion thereof is freed from engagement 35 with the strip aperture wall and a rearwardly urged mounting carriage supporting said rearward pin for forward and rearward movements substantially in the strip path.

55 8. In a record machine, in combination, a writing platen to which one or a plurality of relatively superposed continuous traveler record strips having apertures may be fed, a strip controlling pin positioned rearwardly of said platen and having a rearwardly facing upwardly inclined lipped portion adapted to engage and enter the strip apertures and a pivotal mounting whereby said pin may be pivotally moved toward and away from strip cooperating position, said pin having opposed to said lipped portion a curved surface with its center of curvature at the same side of the pin as the pivot of said pivotal mounting.

9. In a record machine, in combination, a writing platen to which one or a plurality of relatively superposed continuous traveler record strips having apertures may be fed, a strip controlling pin having a strip aperture engaging lipped portion, and a pivotal mounting whereby 70 said pin may be pivotally moved toward and

away from strip cooperative position, said pin having opposed to said lipped portion, a curved surface with its center of curvature at the same side of the pin as the pivot of said pivotal mounting.

5

10. In a record machine, in combination, a writing platen over which a record strip having apertures may be fed and supported for the reception of an inscription, strip controlling means for controlling the strip on said platen and including a pin mounted to engage strip apertures, means for moving said pin in one direction to free it from engagement with the wall of the strip aperture, and means for subsequently moving said pin in another direction to withdraw it from 15 the aperture.

11. In a record machine, in combination, a writing platen over which a record strip having apertures may be fed and supported for the reception of an inscription, strip controlling means 20 for controlling the strip on said platen and including a pin, a mounting device mounting said pin for forward and rearward movements substantially in the strip path, strip restraining means for holding the strip in writing position 25 upon the platen, operating means for said strip restraining means, and means controlled by said operating means for moving said pin in a direction to free it from engagement with the strip aperture wall when said restraining means is set 30 in strip restraining position.

12. In a record machine, in combination, a writing platen over which a record strip having apertures may be fed and supported for the reception of an inscription, strip controlling means 35 for controlling the strip on said platen and including a pin, a mounting device mounting said pin for forward and rearward movements substantially in the strip path, strip restraining means for holding the strip in writing position 40 upon the platen, operating means for said strip restraining means, means controlled by said operating means for moving said pin in a direction to free it from engagement with the strip aperture wall when said restraining means is set 45 in strip restraining position, and means for subsequently withdrawing said pin from the strip aperture.

13. In a record machine, in combination, a writing platen over which a record strip having 50 apertures may be fed and supported for the reception of an inscription, strip controlling means for controlling the strip on said platen and including a pin, a mounting device mounting said pin for forward and rearward movements substantially in the strip path, strip restraining means for holding the strip in writing position upon the platen, yielding means urging said mounting device and pin to tension the strip, operating means for withdrawing said pin from 60 aperture engaging position, and a holding device controlled by said operating means for holding said mounting device against the action of said yielding means.

14. In a record machine, in combination, a writing platen over which a record strip having apertures may be fed and supported for the reception of an inscription, strip controlling means for controlling the strip on said platen and including a pin, a mounting device mounting said 70 pin for forward and rearward movements substantially in the strip path, strip restraining means for holding the strip in writing position upon the platen, yielding means urging said mounting device and pin to tension the strip, 75

operating means for withdrawing said pin from aperture engaging position, a holding device controlled by said operating means for holding said mounting device against the action of said yielding means and means for releasing said holding device after a predetermined movement of said operating means.

15. In a strip controlling device, in combination, a strip controlling pin having a strip aperture engaging lipped portion facing longitudinally of the strip path, and a pivotal mounting for the pin having its pivot positioned at the lipped side of said pin.

16. In a strip controlling device, in combination, a strip controlling pin having a strip aperture engaging lipped portion facing longitudinally of the strip path, and a pivotal mounting for the pin having its pivot positioned at the lipped side of said pin, said pin having at its side opposed to the lipped side a curved surface having its center of curvature at the same side of the pin as said pivot.

17. In a strip controlling device, in combination, a strip controlling pin having a strip aperture engaging lipped portion facing longitudinally of the strip path, and a pivotal mounting for the pin having its pivot positioned at the lipped side of said pin, said pin having at its side opposed to the lipped side a surface convexed laterally and longitudinally of the pin axis, said longitudinally convexed surface having its center of curvature positioned at the same side of the pin as said pivot.

18. A strip controlling device including, in combination, a pin mounted for yieldingly resisted movement and positioned to enter strip apertures so as to exert strip tensioning and control as the strip is moved in its path, strip restraining means for holding the strip in position to which it has been moved, and operating means for setting said restraining means in strip holding condition following said tensioning action by said pin and then moving said pin in a direction to free it from engagement with the strip aperture wall, so as to transfer the strip tensioning and controlling restraint from said pin to said restraining means.

19. A strip controlling device including, in

combination, a pin mounted for yieldingly resisted movement and positioned to enter strip apertures so as to exert strip tensioning and control as the strip is moved in its path, said pin having a lipped aperture engaging portion faced longitudinally of the strip path, strip restraining means for holding the strip in position to which it has been moved and operating means for setting said restraining means in strip holding condition and then moving said pin to free the lipped side thereof from engagement with the strip aperture wall.

20. A strip controlling device including, in combination, a pin mounted for yieldingly resisted movement and positioned to enter strip apertures so as to exert strip tensioning and control as the strip is moved in its path, said pin having a lipped aperture engaging portion faced longitudinally of the strip path, strip restraining means for holding the strip in position to which it has been moved, operating means for setting said restraining means in strip holding condition and then moving said pin to free the lipped side thereof from engagement with the strip aperture wall and means for subsequently withdrawing the pin from the aperture while in its said aperture freeing position.

21. A strip controlling device including, in combination, a pin mounted for yieldingly resisted movement and positioned to enter strip apertures so as to exert strip tensioning and control as the strip is moved in its path, said pin having a lipped aperture engaging portion faced longitudinally of the strip path, strip restraining means for holding the strip in position to which it has been moved, operating means for setting said restraining means in strip holding condition and then moving said pin to free the lipped side thereof from engagement with the strip aperture wall and pivotal mounting means mounting said pin for movement away from strip aperture engaging position with a strip freeing movement, said operating means including a member having an automatic coupling connection with the pivotally mounted pin for moving the latter on its pivotal mounting away from strip engaging position.

CARL ROBERT MABON.
